CHARLES HAMMER, OF HOLLIS COURT BOULEVARD, NEW YORK.

METAL CAP.

Application filed February 16, 1924. Serial No. 693,174.

To all whom it may concern:

Be it known that I, CHARLES HAMMER, a citizen of the United States, residing at Hollis Court Boulevard, in the county of 5 Queens and State of New York, have invented certain new and useful Improvements in Metal Caps, of which the following is a specification.

This invention relates to containers and 10 caps therefor, particularly to glass containers, such as catchup bottles and to metal caps for sealing the same, the object of the invention being to provide an improved glass container and pry-off cap which later 15 can be made of relatively thin sheet metal and readily attached and easily removed by the use of a convenient pry-off means such as a coin and which cap is of simple construction, easily manufactured, 20 inexpensively produced and efficient in use, and which can be either snapped on for reuse or rotated into locked position.

In the present improvement the cap and 25 the container are provided with cooperating holding means located above the strengthened edge of the cap and comprise an annular shoulder and an annular bead one of which as the shoulder, is formed of spaced projections around the same, where- 30 by in this form of the improvement the cap may, in its reuse be either snapped on or rotated into locking position.

In the drawings accompanying and forming 35 a part of this specification, Fig. 1 illustrates this improved glass container in the form of a catchup bottle having one form of this improved cap applied thereto, the cap being shown in section; Fig. 2 is a side view of the cap applied to the bottle; and 40 Fig. 3 is a cross sectional view taken on line 3—3 Fig. 1.

Similar characters of reference indicate 45 corresponding parts in the several views.

Before explaining in detail the present improvement and mode of operation thereof, it is desired to have it understood that the invention is not limited to the details of construction and arrangement of parts 50 which are illustrated in the accompanying drawings, since the invention is capable of other embodiments, and that the phraseology which is employed is for the purpose of description and not of limitation.

The glass container is shown as a catchup 55 bottle 2, and comprises a body having a ta-

pering neck 3 provided with a rounded lip or mouth 4 and spaced below and of larger diameter an annular shoulder 5, and spaced below and of still larger diameter a shoulder 6 facing the shoulder 5. In this form of 60 container the shoulder 5 is formed by an annular band 5'. The shoulder 6 is connected with the shoulder 5 by an inwardly curved portion 9 and a straight portion 10, the shoulder 6 having a relatively flat upper face 65 11 and tapers toward the neck of the bottle 12 from which point the bottle flares toward the body.

The shoulder shown is formed of spaced 70 projections 5'' located at intervals around the container. In other words the shoulder 5 is not a continuous shoulder but is formed of separated or spaced holding portions 5''. Between these spaced portions 5'' there is either no shoulder at all or one of small 75 portions as compared with the portions 5''.

The improved cap shown in Fig. 1 comprises a two-piece cap, although in some forms thereof, particularly when the skirt is of less depth, the cap may be made in one 80 piece. As shown, the top thereof comprises a disc 13 seamed or interlocked with a depending seamed skirt or flange 14, which may have corrugations if desired to assist in the manipulation of the cap as well as 85 to strengthen the skirt of the same. The depending skirt which may be of any suitable depth, is in the present instance shown of that depth which is particularly adapted 90 for use as a catchup cap, and therefore the skirt is shown as having a depth usually as great as the diameter of the cap. The lower edge of the skirt is bent upon itself to form a curled, rolled, beaded or stiffened lower edge 15 frequently called in this art 95 a wire edge, although no wire is therein.

Above this rolled or beaded edge 15 the unstiffened metal of the skirt is inset or impressed as at 16 around the cap to form an annular continuous holding bead underlapping the spaced formed shoulder 5 of the container. This insetting is done in the first instance when the bottle is sealed by a suitable machine whereupon the container is efficiently sealed. Of course in practice the 100 cap could be inset only under the projecting portions 5'' of the shoulder 5, but it is found preferable in the construction shown in Figs. 1 to 3 to continuously inset the cap 105 all around the same.

In the hands of the user however, the cap can be readily removed or pried off by the insertion of a coin 17 under the rolled edge, and between it and the shoulder 6 of the container. When it is desired to reseal the bottle the cap can be readily snapped on again, and subsequently removed in the same manner, but as the cap, when it is pried off by the use of a coin, is likely to have those portions of its annular bead 16, which registered with the projecting portions 5" of a container shoulder somewhat flattened or ironed out or deformed by the removal of the cap, of course the cap may not hold as efficiently if resnapped on in the same position as when applied by the manufacturer, but as those portions of the annular bead 16 which registered with the spaces between the projections 5" will not be flattened or ironed out on the removal of the cap, it follows that in the reuse of the cap it may be applied to the bottle with such undeformed portions registering with the spaces of the container shoulder and then the cap rotated to bring such undeformed portions under the projecting shoulder portions 5", thus securing the cap with practically the same efficiency in its reuse as it was originally secured by the manufacturer.

In other words when the annular bead 16 is inset by the machine under the projecting portions 5" it will also be inset adjacent to the spaces between these projecting portions 5", this being done by means of the machine which is formed for that purpose, and consequently when the cap is removed by a coin those portions of the annular bead 16 which underlap the projecting portions 5" of the shoulder will be somewhat flattened out, but those portions which register with the spaces of the container shoulder will retain their form, and consequently when the cap is re-applied to the bottle these latter portions can register with the spaces in the shoulder so that the cap can be pushed down on to the bottle and then turned to bring the unironed or undeformed portions of the bead under the projecting portions 5" of the container, thus again securely holding the cap on the container, or if preferred the cap can be snapped on provided the somewhat ironed out portions are registered with the projections 5" of the container. Thus in the construction shown the cap can be either snapped on or rotated on.

In the form of cap shown it can be more easily pried off than is possible where the cap has a continuous annular bead holding under a continuous annular shoulder of the container. Consequently as the cap in the present structure is shown held at four points, although a greater or less number could be used if desired instead of all around the container shoulder, obviously it can be more quickly released by the use of a coin

or other pry-off instrument than is possible where a continuous bead on the cap underlaps a continuous shoulder on the container, and also obviously the cap can be snapped on easier than where the cooperating holding means comprises a continuous shoulder and a continuous bead, since the metal of the cap will give or release at the four points much more quickly and easily than it would where the cap is held by a continuous shoulder and a continuous bead. 75

The cap it will be seen has a comparatively smooth interior free from any threads or holding lugs or any means to become messed up and clogged by the contents of the container, thus providing a highly sanitary and practical cap in which the holding means is located above the lower strengthened or rolled edge of the cap, but adjacent thereto. In the form of cap shown this holding means is in the form of an annular continuous impressed bead. This holding portion is entirely independent of the rolled edge of the cap and formed of the unstiffened metal of the cap itself above and free of the stiffened or rolled edge, so that the bending inward of the skirt will not effect such rolled edge. Thus the cap has in the present instance an annular holding portion located above a continuous out-turned rolled edge, the skirt metal between the two flaring outward as at 18 whereby a coin or other instrument may be readily inserted and leverage used against the curled edge and lower shoulder 6, which forms the fulcrum for the coin, to pry off the cap. 95

Thus, while the holding portion of the cap and the out-turned curled edge are located in close proximity to each other whereby one strengthens and reinforces the other, they are nevertheless so spaced from each other by the flaring part 18 that the action of one is not interfered with by the other, and yet both are located at the lower portion of the cap, thus leaving the entire inner surface of the cap from near the lower edge thereof to the top free of any inward holding projections, threads or other means to become filled up and corroded by the bottle contents. 110

By means of the present improvement, I am able to provide a thin sheet metal cap which can be readily made without the use of threads or other similar holding means, and in which the lower edge of the cap can be strengthened by means of a rolled or curled portion, which makes the cap sanitary and free of the disadvantages present in a raw or free edge cap, while the rolled edge so strengthens or stiffens the lower edge of the cap that a coin may be used to engage this lower strengthened edge to pry off the cap without mutilation or destruction of the edge, although the cap is made of thin metal. The impressed holding portion of the cap 120 125 130

is so located that the impressing thereof to secure it to the bottle will not be interfered with by the reinforced lower edge of be mutilated by any implement used to pry off the cap. Moreover, the metal above the curled edge can be impressed more readily than is possible with the rolled edge, which, because of its stiffened formation resists such inward pressure and also resists the prying off of the cap.

Consequently the present cap can be more readily removed by the use of a coin as the impressed holding portions yield more quickly than would the stiffened lower edge were this bent under the container shoulder, and will yield more quickly than is possible where the holding portions are of continuous form on both cap and container.

Most catchup caps heretofore devised have usually been provided with threads requiring the glass neck of the bottle to be similarly formed and there are certain disadvantages in such constructions other than those already pointed out, among which are the expense of forming the caps with threads as well as the bottle, and the time required to turn the cap on and off, all of which are material factors in the manufacture and quick handling of devices of this kind. Aside from this, the ordinary threaded catchup cap required a separate sealing medium for the bottle usually in the form of a separate cap or cork, which the present improved cap does away with, thus enabling this cap to not only take the place of two but to be made at much less expense, to be more easily handled and more quickly applied, as well as removed, and also more efficiently used.

Thus I have provided an improved cap comprising a top and a depending skirt having a curled or rolled lower edge thus materially simplifying and reducing the cost of manufacture thereof. The cap is merely placed on the bottle and by a suitable machine the metal above the rolled edge is inset under the shoulder of the container, whereby the cap is efficiently held onto the bottle. Subsequently the purchaser of the sealed package can by the use of a mere coin quickly pry off the cap, and when it is desired to reseal the bottle the cap can be readily snapped on, or rotated on.

Thus I have I believe, provided a very inexpensive, easily handled and applied catchup cap.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although with-

out attempting to set forth all of the forms in which it may be made, or all of the modes of its use, I claim:

1. The combination of a container provided with an annular shoulder formed of spaced holding portions, and a metal cap comprising a top and a depending skirt having above its lower edge an impressed annular bead cooperating with the spaced holding portions of the container, the prying off of the cap serving to deform or iron out those portions of the bead cooperating with the spaced holding portions of the container leaving the undeformed portions of the cap bead in position to subsequently register with the spaced holding portions of the container whereby the cap may be either snapped or rotated on to the container.

2. The combination of a glass container provided with an annular shoulder formed of spaced holding portions and a metal cap comprising a top and a depending skirt having a stiffened lower edge, and thereabove an impressed annular bead cooperating with the spaced holding portions of the container, the prying off of the cap serving to deform or iron out those portions of the bead cooperating with the spaced holding portions of the container leaving the undeformed portions of the cap bead in position to subsequently register with the spaced holding portions of the container whereby the cap may be either snapped or rotated on to the container.

3. The combination of a container provided with annular spaced holding portions, and a metal pry-off cap comprising a top and a depending skirt having above its lower edge a cooperating holding portion to engage the under wall of said spaced holding portions and so deformed by the prying off of the cap that the cap may be thereafter either snapped on or rotated on to the container.

4. The combination of a container provided with annular spaced holding portions, and a metal pry-off cap comprising a top and a depending skirt having a strengthened lower edge and above its lower edge a holding bead so deformed by the prying off of the cap that the cap may be thereafter either snapped on or rotated on to the container.

5. The combination of a container provided with annular spaced holding portions, and a metal pry-off cap comprising a top and a depending skirt having a strengthened or beaded lower edge and above its lower edge a holding bead so deformed by the prying off of the cap that the cap may be thereafter either snapped on or rotated on to the container, the metal of the skirt between said beads flaring outward thereby to permit the insertion of a coin between the beaded lower edge and the container to pry off the cap.

6. A metal cap having a depending skirt having an inwardly extending annular bead functioning under the shoulder portion of a container as the holding element of the cap and immediately below and independent of said holding element a stiffened curled or beaded lower edge, the metal of the skirt between said beads flaring outwardly by means of which and the strengthened lower edge of the cap a coin may be inserted for prying off the cap, said cap holding element being deformed during the prying off of the cap and leaving an undeformed holding portion for use during the subsequent application of the cap to the container.
7. A metal cap comprising a top and a depending skirt having above the lower edge thereof an impressed annular holding bead to engage under a container shoulder, spaced portions of said bead being deformed on the prying off of the cap to leave in said bead spaced holding portions.
8. A metal cap comprising a top and a depending skirt having a stiffened lower edge and above said stiffened lower edge an impressed annular holding bead to engage under a container shoulder, spaced portions of said bead being deformed on the prying off of the cap to leave in said bead spaced holding portions.
9. A metal cap comprising a top and a depending skirt having a stiffened lower edge and above said stiffened lower edge an impressed annular holding bead to engage under a container shoulder, spaced portions of said bead being deformed on the prying off of the cap to leave in said bead spaced holding portions, the metal between said stiffened lower edge and holding bead flaring outwardly to permit the cap to be pried off.
10. A metal catchup cap comprising a top and a long depending skirt having an outwardly stiffened lower edge, and above it but in proximity thereto an impressed annular bead to engage under a container shoulder, spaced portions of said bead being deformed on the prying off of the cap to leave in said bead spaced holding portions, the metal between said lower edge and holding bead flaring outwardly to permit the insertion of a pry-off means.
11. The combination of a container and a pry-off metal cap adapted for use therewith, and comprising a top and a depending skirt having a stiffened or beaded lower edge spaced from the side of the container to permit the insertion of a pry-off means, said container and skirt having cooperating holding portions above the lower edge of the cap, each comprising an annular portion, the holding portion of the cap being machine-set under the container holding portion subsequent to the application of the cap to the container and functioning as the holding element of the cap on to the container, the annular holding portion of the container comprising spaced portions, whereby on the deformation of the annular holding portions of the cap at intervals other than similar holding portions enable the cap to be rotated on to the container.

Signed at Brooklyn, N. Y., this 13th day of February 1924.

CHARLES HAMMER.
